UNITED STATES PATENT OFFICE.

ALFRED W. F. GUEST, OF BROOKLYN, NEW YORK, ASSIGNOR TO MERGENTHALER LINOTYPE COMPANY, A CORPORATION OF NEW YORK.

TYPOGRAPHICAL MACHINE.

1,088,698.

Specification of Letters Patent.

Patented Mar. 3, 1914.

Application filed April 11, 1913. Serial No. 760,375.

To all whom it may concern:

Be it known that I, ALFRED W. F. GUEST, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices are released from a magazine or magazines in the order in which their characters are to appear in print and then assembled in line, the composed line transferred to the face of a mold, the mold filled with molten 20 metal to form a slug or linotype against the matrices which produce the type characters thereon, and the matrices thereafter returned through a distributing mechanism to the magazine from which they started.

25 More particularly, the invention relates to the distributing mechanism, and is shown by way of example and in preferred form in connection with a special kind of machine, wherein a plurality of distributor 30 are arranged in associated relation to each other. However, it will be apparent that my improvements may be similarly employed in connection with a single distributor, and that no limitation is imposed by their present mode of illustration. In the Mergenthaler patent above mentioned, the distributing devices comprise rotating screws which convey the matrices along a grooved rail or bar, from which they are released at 35 the proper points to return them to the appropriate channels in the magazine, and my invention is herein set forth in connection with that specific mechanism. Obviously, 40 however, the principles thereof are capable of far broader application, and may be adapted to distinctly different styles of distributor, as well as to other forms of typographical machines, as for instance those 45 which handle type or dies instead of matrices.

Generally speaking, I desire it to be understood that I do not limit myself to any specific form or embodiment, except in so far as such limitations are specified in the 50 claims.

The application for Letters Patent of J. R. Rogers, Serial No. 687,691, filed April 1, 1912, discloses means to arrest positively the rotating distributor screws, in the event that a type or matrix while in relation thereto is improperly retarded, as for instance, if it becomes lodged in the entrance to a magazine and there resists the operation of the screw. The screws are ordinarily synchronously rotated or operated, and in the said application the parts are so arranged that in the event of undue resistance or other similar derangement, this synchronism will be interrupted, thereby calling into action certain connected devices, which ordinarily run freely, but in such circumstances are thrown out of their normal relations, and as a result thereof interfere and contact with each other so as positively to arrest the further operation of the screws. In connection with these 75 devices, I propose to employ special means for disengaging the driving mechanism in the event that the operation of the distributing devices is retarded, whether this happens because of the action of the parts 80 already described or in some totally different manner. In other words, although this feature may be employed advantageously with the described means for positively arresting the screws, it is similarly applicable 85 to any form of distributor or other mechanism, wherein it may be desired to unclutch or otherwise disengage the driving means in the event of the arrest or retardation of the driven parts.

90 In the employment of the specific mechanism above referred to, it sometimes happens, after the screws are arrested, that an appreciable period of time elapses before the actual disengagement of the driving 95 means, thus submitting the parts to undue strain and possibly to bending or breakage.

It is the principal object of my invention to effect the disengagement of the driving means, or in the form shown, the breaking 10 of the clutch, instantaneously, so as to make the stop mechanism more responsive and thus to reduce the objectionable strain on the parts already mentioned.

Referring to the drawings: Figure 1 is a 105 side view, partly in section, and broken away, of the distributing mechanism and its driving means, with my invention applied thereto; Fig. 2 is a sectional view, taken substantially on the line 2—2 of Fig. 1; Fig. 110

3 is a detail of the tripping devices, etc.; Fig. 4 is a plan view, partly in section; and Fig. 5 is a similar view, showing the parts in different position.

5 The matrices X are, as usual, conveyed along the distributor rail Y by the rotating screws D, and drop therefrom into their appropriate magazine channels. The screws D are rotated from the driving wheel A through the clutch member B, which rotates 10 the sprocket wheel C in the manner subsequently to be described, and thence through the sprocket chain C¹, sprocket wheel C², and gearing C³ connected to the screws. Except for the differences subsequently to be described, these parts and their mode of operation are or may be substantially the same as those disclosed in the said Rogers application.

20 Certain of the screws D are provided with the disks D¹ substantially similar to those disclosed in the application for Letters Patent of A. P. Paine, Serial No. 704,958, filed June 21, 1912, constituting supplemental 25 means for retarding or arresting the distributing mechanism. These disks are preferably formed with inclined or spiral flanges, and are so arranged that in ordinary operation they run freely in relation to each other, but with their respective flanges 30 or threads always in lateral proximity. If for any reason, (such as undue resistance or the like, as for instance when the matrices X become jammed, as indicated in Fig. 2), the 35 synchronism of the screws be interrupted, the disks will be shifted in angular relation to each other, resulting in the lateral contact of their respective flanges and consequently the immediate and positive arrest of the 40 screws. The stoppage of the screws reacts through the sprocket chain C¹ and arrests the sprocket wheel C and thus resists the driving means, which action and resistance are utilized to effect the instantaneous disconnection of the clutch member B in the manner subsequently to be described.

The clutch member B is mounted upon the sleeve E, which sleeve is normally pressed into operative position by the spring B¹ in 50 such manner as to engage the clutch member with the wheel A. The sprocket wheel C is attached to the nut S, also mounted upon the sleeve E and engaging therewith by the screw-threaded connection T, in such manner that when the nut is rotated on the sleeve, it is also given a slight lateral movement with relation thereto. Rotary motion is imparted to the sprocket wheel C by the spring F, connected thereto and to the clutch 55 member B, the spring having sufficient strength to cause the parts normally to rotate in unison, but adapted to permit a relative movement between them when the sprocket wheel C is retarded in the manner 60 previously mentioned.

In normal operation, the strength of the spring B¹ is adequate to cause a driving connection between the clutch member B and wheel A. This action is, however, controlled and overcome, when the distributing 70 devices are arrested or retarded, by the toggle joint JK and the more powerful spring G, whereby the immediate breakage of the clutch is effected. The toggle member J is pivoted at one end to the frame portion M, 75 and at its other end to the toggle member K, which is centrally pivoted on the frame portion N. The slide H is connected at one end to the toggle members J and K at their point of junction, and at its other end to the spring 80 G, the parts being so arranged as normally to straighten the toggle joint JK, and bring the end K¹ of the member K into contact with the flange L mounted upon the sleeve E, thereby overcoming the force of the spring 85 B¹, and breaking the clutch connection, as indicated in Fig. 5.

The actuating devices are provided with the pivotally mounted setting handle O, formed at its upper end with the projecting 90 portion O¹ adapted to engage the slide H, in such manner that when the handle is moved to the full line position of Fig. 1, the toggle joint JK is broken and the spring G placed under tension, as indicated also in 95 Figs. 2 and 4. In this condition of the parts the clutch member B is held in operative relation to the driving wheel A by the spring B¹, and in order to permit the continued actuation of the distributing mechanism, the 100 handle O is provided with the detent P, pivotally connected thereto and actuated by the spring P¹ to hold it normally in engaging relation to the fixed stop R. When the handle O is moved to operative position in the 105 manner described, the projecting head P² of the detent P is simultaneously brought into engagement with the circumferential groove S¹ of the nut S, (see Figs. 1 and 2).

The parts continue to operate until the 110 distributing mechanism is retarded in the manner previously described, the result of which retardation is the arrest of the sprocket chain C¹, wheel C, and connected nut S, when the elongation of the spring F permits 115 the rotary movement of the nut S with reference to the moving sleeve E, and due to the screw-thread connection T, its lateral relative movement on the sleeve. The lateral shifting of the nut on the sleeve, due 120 to the engagement of the groove S¹ with the head P² on the detent P, shifts the latter about its pivot and frees it from the stop R, (see Fig. 3), whereupon the handle O drops to the dotted line position shown in 125 Fig. 1, the spring G is permitted to act, the toggle JK is straightened thereby, and through the engagement of the toggle head K¹ with the flange L, the sleeve E is shifted 130 rearwardly against the force of the spring B¹,

thereby breaking the connection between the clutch member B and the driving wheel A, as indicated in Fig. 5. It will be seen that due to this construction and mode of operation, the powerful spring G is permitted to act practically instantaneously to break the driving connection, and thus to minimize the liability to strain or breakage or bending.

10 As previously pointed out, I have shown my invention only in preferred form and by way of example, but obviously many variations and modifications therein, and in its mode of application, will suggest themselves 15 to those skilled in the art without departure from its scope.

Having thus described my invention, its construction and mode of operation, what I claim and desire to secure by Letters Patent of the United States is, as follows:

1. In a typographical machine, the combination of distributing mechanism, actuating devices therefor, supplemental means connected to the distributing mechanism for retarding or arresting the same, and connections whereby the retardation of the distributing mechanism will instantly effect the arrest of the actuating devices.

2. In a typographical machine, the combination of distributing mechanism, actuating devices connected thereto, supplemental means connected to the distributing mechanism for retarding or arresting the same, and means tending constantly to disconnect 35 the actuating devices from the distributing mechanism and adapted to be rendered effective upon the retardation thereof.

3. In a typographical machine, the combination of distributing mechanism adapted to 40 be retarded by misplaced type or matrices, and actuating devices therefor, the said actuating devices comprising a clutch and a spring for opening the clutch directly when the distributing mechanism is retarded.

45 4. In a typographical machine, the combination of distributing mechanism and actuating means therefor, the said actuating means comprising a clutch, a spring to close the clutch, and a second spring of sufficient 50 strength to overcome the other and open the clutch, the second spring adapted to be thrown into action upon the abnormal operation of the distributing mechanism.

5. In a typographical machine, the combination of distributing mechanism and actuating means therefor, the said actuating means comprising a clutch, a spring to close the clutch, a second spring of sufficient strength to overcome the other and open the clutch, and devices for holding the second spring against action to permit 60 the other spring to close the clutch, the said device adapted to be tripped upon the abnormal operation of the distributing mechanism.

6. In a typographical machine, the combination of distributing mechanism and actuating means therefor, the said actuating means comprising a driving part and a driven part, the latter being formed with a relatively movable section connected to the distributing mechanism and controlled in its relative movement by the abnormal operation thereof, a spring, normally inactive, to disengage the driving and driven parts, and connections whereby the relative movement of said section will render the spring active.

7. In a typographical machine, the combination of distributing mechanism and actuating means therefor, the said actuating means comprising a driving part and a driven part, the latter being formed with a relatively movable section connected to the distributing mechanism and controlled in its relative movement by the abnormal operation thereof, a spring, normally inactive, to disengage the driving and driven parts, and devices, adapted to be tripped by the relative movement of the said section, for holding the spring against action.

8. In a typographical machine, the combination of distributing mechanism and actuating means therefor, the said actuating means comprising a driving part and a driven part, the latter having a driving gear mounted to move relatively thereto when retarded by the distributing mechanism, and a spring rendered active by the relative movement of the said gear to disengage the driving and driven parts.

9. In a typographical machine, the combination of distributing mechanism and actuating means therefor, the said actuating means comprising a clutch, a spring to close the clutch, and a second spring of sufficient strength to overcome the other and open the clutch, the second spring being thrown into action upon the abnormal operation of the distributing mechanism, together with means for restoring the parts to their original position.

10. In a typographical machine, the combination of distributing mechanism and actuating means therefor, the said actuating means comprising a driving part and a driven part, the latter being formed with a relatively movable section connected to the distributing mechanism and controlled in its relative movement by the abnormal operation thereof, a spring, normally inactive, to disengage the driving and driven parts, and connections whereby the relative movement of said section will render the spring active, together with means for resetting the parts in their original position.

11. In a typographical machine, the combination of distributing mechanism, actuating means therefor, the said actuating means comprising a clutch, a spring to open the clutch directly, and means for holding said

spring out of action to permit the clutch to be closed, the said means adapted to be tripped by the continued operation of the actuating means upon the abnormal operation of the distributing mechanism.

12. In a typographical machine, the combination of distributing mechanism and actuating means therefor, the said actuating means comprising a clutch and a spring for opening the clutch directly, the said spring being permitted to act upon the abnormal operation of the distributing mechanism, and means for resetting the parts in operative relation.
13. In a typographical machine, the com-

bination of distributing mechanism and actuating means therefor, the said actuating means comprising a clutch, a spring to open the clutch directly, and devices, adapted to be tripped upon the abnormal operation of the distributing mechanism, for holding the spring out of action, together with means for resetting the said devices to permit the clutch to be closed.

In testimony whereof I have affixed my signature in presence of two witnesses.

ALFRED W. F. GUEST.
